WIRE FASTENING DEVICE

Bror August Fredell, San Jose, Calif.

Application November 10, 1939, Serial No. 303,799

2 Claims. (Cl. 140—55)

In the construction of wire fences it is common practice to erect spaced metal posts along the fence line, and then fasten the vertically spaced horizontal wires to these posts. Each horizontal 5 wire is secured to each post by means of a short piece of wire hooked on to the post, passed around the fence wire, and then hammered into locking engagement with the post, in a manner herein-after more particularly set forth.

10 This method of securing the fence wire in place is a laborious and time-consuming one, and it is difficult to perform the operation without puncturing, scratching, or otherwise injuring one's hands when barbed wire is used as in practically all cases.

It is, therefore, one object of the invention to provide a tool so constructed and arranged that it may be used to apply the wire fastening above referred to and remove the necessity of bringing 20 the hands into dangerous contact with the barbed wire.

It is another object of the invention to provide a tool of the character indicated constructed and arranged to hold and manipulate the same form 25 of wire fastening now commonly in use.

Finally, it is an object of the invention to provide a tool of the character indicated that will secure the fastening in position with but little effort upon the part of the operator, that will be 30 simple in form and construction, economical to manufacture, strong, durable, and highly efficient in its practical application.

In the drawing:

Figure 1 is a side elevation of a tool embodying my invention, in operative relation to a fence post, a wire thereon, and a fastening therefor, parts being broken away.

Figure 2 is a front elevation of a fence post with one wire and its fastening thereon, part 40 broken away.

Figure 3 is a sectional view through the tool, on line 3—3 of Figure 1.

Figure 4 is a section on line 4—4 of Figure 3.

Figure 5 is a view on line 5—5 of Figure 1.

45 The tool comprises a pair of crossed handle members 1 and 2 with a pivotal connection at 3 and having a spring inserted between them as at 4 to urge them apart. The two handles terminate in jaws as 5 and 6, and in that broad aspect 50 form a pair of pliers of the well-known type.

The wire most commonly used as a fastener is formed as shown at 7. It has an arcuate portion 8 adjacent one end 9, which end is turned back upon itself to form a hook 10, the other 55 end 11 being considerably longer than end 9 and

disposed in angular relation to arcuate portion 8 and in opposed relation to end 9.

The entire wire is formed to lie in a single plane. In the process of applying it the end 9 is hooked over edge 10a of the post 12, the arcuate portion 8 is passed over the fence wire 13 crossing the front of the post, and the end 11 takes the position shown in solid lines in Figure 1, extending a distance beyond the rear edge of the post 12.

As hereinbefore stated it has heretofore been the custom to hammer this rearwardly projecting end of the wire around the rear edge of the post until it assumed the position shown in dotted lines at 14, in which final position the wire forms 15 a secure clamp for the fence wire 13, but I have so formed the jaws 5 and 6 of the tool shown that the same result may be more easily and quickly obtained without the use of a hammer or other tool or implement.

In accordance with my invention the lower jaw 5 of the tool terminates in an inwardly directed portion 15 and has a groove 16 formed in the center of its inner edge and extending throughout the length thereof. The inner edge 20 17 conforms to the curvature of the wire and consequently the groove 16 forms a seat for the portions 8 and 9 of the wire.

The jaw 6 is somewhat longer than jaw 5 and terminates in a head 18 that is directed toward 30 jaw 5 and forms an acute angle with the body of the jaw as at 19. Formed in the end of head 18 is a notch 20, this notch being disposed to lie in the plane of the groove 16 so that when a wire 7 is seated in groove 16 the end 11 will seat 35 in the notch 20 as shown.

Extending crosswise of the head 18 on the inner side thereof, and immediately back of the notch 20, is formed a boss 21. The several parts of the tool are so proportioned that when it is in position as shown in Figure 1 and the jaw 6 advanced toward jaw 5 the boss 21 will pass over the rear edge of the post 12 with just sufficient clearance to permit the wire 7 to lie between.

In using the tool, the wire 7 having been previously formed as shown in solid lines in Figure 1, the said wire is seated in groove 16 as described with its straight end seated in notch 20. The fence wire 13 is placed across the face of post 12, and then the jaw 5 with the wire 7 seated therein is hooked over one edge 10 of the post on one side of the fence wire 13, the other jaw 6 extending rearwardly of the post on the other side of the fence wire 13. When so placed the angle 22 in wire 7 formed by the two por- 55

- tions 8 and 11 seats against the edge 23 of the post, consequently when the handles 1 and 2 are compressed and the jaw 6 advanced relative to jaw 5 the straight portion of the wire 11 is bent 5 in the same direction until it strikes the post at 24. In continuing the movement of jaw 6 the wire is forced to bend over the rear edge of the post through the position 25 to its final clamping position as 14.
- 10 Although but one specific embodiment of the invention has been herein illustrated and described, it will be understood that various alterations in the details of construction and mode of assembly may be made without departing from 15 the scope of the invention as indicated in the appended claims.

I claim:

1. A tool for applying and securing to a post a wire clamp having a hook formed on one end

and a straight angularly directed shank formed on the other end comprising, a pair of pliers having one jaw formed into a hook-shaped end portion having a groove formed therein to extend through the length of its inner side to form a seat 5 for the hooked portion of the wire, the other jaw being longer and terminating in a head portion directed toward the end of the first jaw and disposed at an acute angle to its body portion, and having a terminal notch formed therein in opposed relation to the groove in the first jaw and disposed to form a seat for the free end of the straight portion of the wire.

2. The device set forth in claim 1 wherein the longer jaw has a raised portion formed on the 15 inner side of its head portion at the base of the terminal notch.

BROR AUGUST FREDELL.
